TYPEWRITING MACHINE

Henry L. Pitman, Westfield, N. J., assignor to
 Underwood Elliott Fisher Company, New York,
 N. Y., a corporation of Delaware

Application September 21, 1933, Serial No. 690,301

21 Claims. (Cl. 197—82)

This invention relates to universal-bar mechanism for the ribbon-vibrator and escapement of typewriting machines, and one of its aims is to eliminate the liability of overthrowing or crumpling the vibrating ribbon.

It is usual for a common universal-bar stroke to effect simultaneously the escapement-operation and full amplitude of ribbon-vibration, the stroke having the high speed or staccato characteristic due to the desirability of working the escapement quickly.

Because the ribbon is vibrated very fast, it is liable to overthrow, which causes "bleeding" in a two-color ribbon. It is further liable to crumpling, which, at high speed, is due to inertia of the ribbon relatively to the rapidly starting ribbon-vibrator.

It remains desirable to localize the universal-bar mechanism at the region of the machine where it can be operated by a type-carrier which, swinging in the usual wide arc, is the member best capable, by reason of its momentum at the end-portion of its swing followed by immediate recoil, of imparting the desired staccato impulse to the universal bar.

In the standard Underwood typing machine, for example, each of the arcuately-arrayed swinging type-bars has near its fulcrum a heel to actuate a single curved universal bar common to the escapement and ribbon-vibrating devices, and which universal bar, in order to secure its staccato actuation, is only engaged by said heel at the final portion of the printing stroke. It will be evident that when such common universal bar and cooperating heel are used, the limit to which the speed of ribbon-vibration can be forced, limitedly determines the speed of the universal bar and hence, largely, the speed of the carriage-feed.

In practicing the present invention, a universal-bar-actuating portion of the type-bar or other similarly moving type-action member is arranged relatively to a novel localized universal-bar mechanism in such a way that the ribbon-movement to the printing point does not wait for the carriage-escapement operation, but starts substantially as soon as the type-bar leaves its normal position, and may continue substantially throughout the printing stroke. The movement of the ribbon to the printing point is thus protracted, and it may be effected with smooth acceleration. Thus there is eliminated the liability of either overthrowing or crumpling the ribbon. Said universal-bar-actuating portion of the type-action member is further arranged relatively to

the novel localized universal-bar mechanism, so that the escapement-actuating phase in the operation of said mechanism has the desired staccato characteristic, whereby the escapement is actuated in immediate correlation to, that is, 5 very close to, the instant of type-impact, and it is feasible therefore to use a speed escapement with consequent benefit to the key-touch.

To these ends, the universal bar is preferably made in two parts, mounted for individual movement, and which parts present two universal faces or edges which may be disposed next to one another in accordance with the idea of localizing the universal-bar mechanism. One of the universal-bar parts is connected to operate the ribbon-vibrator, its universal face or edge being engaged preferably by a cam on the swinging type-bar or similarly moving type-action member, and operative to impart the relatively slow movement to said ribbon-vibrating universal-bar 10 part. The other universal-bar part operates the carriage-escapement, and its face or edge is engaged by a formation on the type-action member, so disposed that it comes into play very close to the instant of type-impact, so that the desired 15 quick operation of the carriage-escapement is effected.

In the Underwood type of machine, the two universal faces or edges of the individually-movable universal-bar parts may be arcuate to conform with the arcuate array of the type-bars, each of the latter being provided with said ribbon-vibrating cam and said escapement-actuating formation. Said arcuate universal-bar parts may be nested one above the other, so that they 35 occupy very little more room than was heretofore occupied by the single universal bar.

The arrangement of the novel universal bars may be such that the connections therefrom to operate the carriage-escapement and ribbon-vibrator may remain practically unaltered in respect to the connections used in prior machines, and the novel universal-bar mechanism may therefore be applied to existing types of machines at little expense.

Certain features of the invention may also be made available with substantial benefit by means of a single universal bar having a universal face or edge formation, which is engageable, during the printing stroke, first by the protractedly-operating ribbon-vibrating cam of the type-action member, and then by a part on said type-action member, which part overhauls the single universal bar and gives the same a staccato impulse very close to the instant of type-impact, and, at 55

the beginning of which impulse, said universal bar has reached the end of approach to, and has thereby become engaged with, a carriage-escapement-operating member.

- 5 A further feature of invention relates to novel devices for facilitating adjustment of universal-bar-mechanism parts at the interior of the machine, and ordinarily inaccessible for manipulation.
- 10 Other features and advantages will hereinafter appear.

In the accompanying drawings,

Figure 1 is a perspective view of the novel two-part universal-bar mechanism, indicating the 15 type-bar and its novel heel-portion in normal position, and the corresponding positions of the two individually movable parts of said mechanism.

Figure 2 is a side view indicating the universal-bar parts seen in Figure 1, and the connections 20 therefrom to the ribbon-vibrator and to the carriage-escapement.

Figure 3 is a side view showing the type-bar as having been swung to the point whereas its cam 25 has actuated one universal-bar part to bring the ribbon, at relatively slow speed, to the printing point; another part of the type-bar heel having started the other universal-bar part, and thereby started operation of the escapement.

30 Figure 4 is a perspective view showing details of novel means for facilitating adjustment of universal-bar springs.

Figure 5 is a perspective view showing the invention as applied to a single universal bar.

35 Figure 6 is a side elevation view showing the single universal bar and its relation to the novel type-bar heel and to the ribbon-vibrating and escapement-operating connections.

Figure 7 is a front elevation view of parts of 40 the organization seen in Figure 6, some of said parts being sectioned and broken away for clearness.

Figure 8 is a side elevation of the universal-bar train and connections of Figure 6, and shows the 45 positions of the parts at the instant of type-impact.

Figure 9 is a fragmentary side view indicating how the type-bar heel-cam may effect the ribbon-vibrating phase of universal-bar movement, and also indicating, in the use of a single 50 universal bar, how the escapement-actuating portion of said heel has overhauled the coacting edge of the single universal bar.

Depression of any alphabet or numeral type- 55 key 10 on key-lever 11, Figure 6, swings, by means of suitable connections, a type-bar 13, pivoted at 14, to print against a platen 15. Said connections may include a bell-crank 17 articulated to the key-lever 11 by a pin-and-slot connection 60 19 and to the type-bar 13 by a link 20, as exemplified in Patent No. 644,082, to Kauffman, of February 27, 1900.

A segment 21 on machine-frame 22 pivotally 65 mounts the system of type-bars 13 in the usual arcuate array seen in Figure 7.

An Underwood platen-carriage is represented in Figures 2 and 6 by a case-shiftable frame 24 forming part of said carriage which has a letter-feeding rack 25 and is driven by the usual spring- 70 motor (not shown) in a letter-feeding step at operation of a type-bar 13.

The novel ribbon and escapement actuating universal-bar mechanism will now be described with reference to its application in the illustrated 75 machine. It may be noted beforehand that the

escapement-mechanism includes the usual escapement-wheel 28 co-operative with the usual dog-rocker 29 having dogs 31 and 32, said escapement-wheel having a pinion 33 meshing with the carriage-rack 25.

5 The universal-bar structure is best made in two parts, one part being arranged to actuate the escapement-dog rocker 29; the other part being arranged to actuate a ribbon-vibrator 36.

As seen in Figure 1, the universal-bar structure includes frames E and R which may be nested together, as shown, to localize said structure in substantially the same region of the machine heretofore occupied by the single universal bar.

10 The frame E has a curved universal bar EU which is concentric with, and is nested within, the curve of a similar universal bar RU of the frame R, said universal bars being engageable by any type-bar 13, as will presently be described.

15 The escapement-universal-bar frame E may be formed to include a front chord 38 having a forwardly-projecting tongue 40 fitted in the type-bar segment 21 to support said frame E at the front for fore-and-aft movement. A rear chord 42 of the frame E has rearwardly-extending side arms 44 connected to a rockable frame 46 to support the rear part of frame E for fore-and-aft movement. A spring 48 yieldably holds the frame E in its forward position determined as 20 by a stop 50 abutting the segment 21.

25 In the ribbon-universal-bar frame R, the universal bar RU has ears 52 having studs 53 fitting the segment 21 to support the front of said frame R for fore-and-aft movement. The frame R has a rear cross-member 56 overlying and clearing the rear chord 42 of frame E and also clearing the escapement-dog rocker 29. Said cross-member 56 of frame R carries one end of the train 30 of ribbon-vibrating connections, and is therefore 35 made adjustable in fore-and-aft directions relatively to the universal bar RU. Rearwardly-extending arms 55 of the universal bar RU therefore overlap and are adjustably secured to fore-and-aft extending side arms 57, Figure 1, of the cross-member 56. Each side arm 57 has a slot 60 to ride as shown, on the rockable frame 46 to support the rear part of frame R for fore-and-aft movement independently of the movement of frame E.

35 Each type-bar 13 has adjacent the type-bar fulcrum 14 a camming edge 62 abutted by the ribbon-universal bar RU when the type-bar 13 is in the normal, Figure 2, position, wherein the type-bar head lies upon a rest 63. Said camming edge 62 may be so formed that beginning with the start of the upward and rearward swing of the type-bar and continuing until the type-bar reaches the Figure 3 position, the ribbon-universal-bar frame R is given a smoothly accelerated and retarded movement indicated by the dotted lines 65, Figure 2, which represent positions of the universal bar RU at equally spaced stages of the swing of the type-bar 13.

40 The movement of frame R, since it is protracted through the described portion of the type-bar stroke, is of relatively slow speed. This slow-speed movement of frame R is transmitted to the ribbon-vibrator 36 through a train of connections which may be of the kind shown in Patent 926,- 45 050, to F. A. Cook, and which may be briefly described as follows. Secured to the usual platen case-shift rail 64 is a lever having an arm 68 connected to the ribbon-vibrator 36, and an arm 70 presenting from each of its opposite lateral 50 75

faces a pin 71. The pins 71 are selectively connectable to the frame R by means of a laterally-slidable bracket 73 (Figure 1), mounted on a flange 74 rising from the rear cross-member 56 of the universal-bar frame R.

If the bracket 73 is shifted to the left, as indicated by the dotted outline 73^a, Figure 7, only the upper pin 71 will be connected to frame R, and hence rearward movement of the latter, as effected by means of camming edge 62 on type-bar 13, will raise the ribbon-vibrator 36 only far enough to bring the upper band of a two-color ribbon to the printing point. A shift of the bracket 73 rightward to the full-line position of Figure 7 will disconnect the upper pin and connect the lower pin 71, whereby the same extent of rearward movement of frame R will bring the lower ribbon-band to the printing point, as indicated in Figure 3. The usual linkage for shifting bracket 73 is indicated by a fragmentary portion 78.

After its rearward movement as far as the Figure 3 position, wherein either the upper or lower band of the ribbon 27 may have been brought fully, if desired, to the printing point, the ribbon-universal-bar frame R may remain stationary in the interval during which the type-bar 13 completes its printing stroke and recoils back to said Figure 3 position. The camming edge 62 of the type-bar 13 may accordingly terminate in a dwell 79 in case the ribbon has been fully vibrated at the Figure 3 position of the type-bar.

During such interval occurring in the operation of the type-bar 13, between the Figure 2 and Figure 3 positions, the carriage-escapement actuation by means of the escapement-universal-bar frame E takes place as an edge or shoulder 80 of the type-bar 13, and in sequence to the cam 62, engages the universal bar EU, as indicated in Figure 3. By the rearward stroke of the frame E thus effected during the further movement of the type-bar 13 from the Figure 3 position, the rear edge of the rear chord 42 of said frame E displaces the dog-rocker 29. This initiates a carriage-feeding step which is completed at the recoil of the type-bar, said recoil resulting in a forward stroke of the frame E under the pull of its spring 48. For a "silent" or non-letter-feeding type-bar the shoulder 80 may be omitted by forming the type-bar 13 as indicated by the dotted line 82, Figure 2.

Accompanying the full return of type-bar 13 from the Figure 3 position to the Figure 2 position, the ribbon-universal-bar frame R moves forwardly under the pull of a spring 83, its universal bar RU following the type-bar cam-edge 62 which may limit the forward movement of said frame as in Figure 2. By said forward movement of the frame R, the ribbon-vibrator 36 is driven down to its normal Figure 2 position determined by abutment of the ribbon-vibrator-actuating arm 68 with a stop-arm 84. There may be an additional stop-arm 85 projecting from the shift-rail 64 and abutting the arm 10 (Figure 2), to determine the lower position of the ribbon-vibrator 36 when the platen is in upper-case position. A stop 86, Figure 2, opposite the ear 52 of frame R, may be provided to limit the rearward movement of said frame R, and said stop may project from machine-frame 22.

To secure proper alignment of the pins 71 of the thus arrested lever 68, 70 with slots 76 of the laterally-shiftable bracket 73, and at the same time to assure abutment of the universal bar RU with the camming edges 62 of the type-bars, said

universal bar RU is made, as before stated, adjustable relatively to the cross-member 56 which carries said bracket 73. The rearwardly-extending arms 55 of said universal bar RU may therefore have elongate holes 87 through which pass 5 screws 88 that secure said arms 55 to the side arms 57 of the cross-member 56.

To facilitate adjustment of the combined length of each pair of arms 55, 57, and hence of the universal bar RU relative to the cross-member 56, these parts being usually at the interior of the machine, and therefore difficult to get at for manipulation, the following novel device may be provided. The screws 88 may be loosened by a screw-driver manipulated from the sides of the 10 machines. For similar manipulation from the sides of the machine for finely adjusting the combined length of a pair of arms 55, 57, each arm 55 may have a slot or opening 89 whose lateral edges are on opposite sides of a hole 90 provided 15 in each side arm 57. The hole 90 receives a fulcrum-tip 91 of an adjusting tool or key 92, Figure 1, manipulatable from the side of the machine and having an edge 93 which, when the fulcrum-tip 91 is inserted in hole 90, serves to move the 20 arm 55 forwardly or rearwardly relative to arm 57, depending on how said key 92 is turned. In this manner, the universal bar RU may be finely 25 adjusted relatively to the cross-member 56 when the screws 88 are loosened, said screws being 30 tightened again when proper adjustment has been effected.

The tension of the universal-bar springs 49 and 83 may also be regulated from the sides of the machine by means of said key 92. Each of said 35 springs is accordingly anchored to a lever 95 mounted on an arm 97. The arms 97 may be combined with the vibrator-stop arm 84 as a unitary fixture 98 attached to an escapement-supporting bracket 34 by screws 99. Each lever 95 may be 40 adjustably fastened to its supporting arm 97 by a screw 100 passing through a slot 101 of said lever. Each supporting arm 97 has a hole 96 into which the fulcrum-tip 91 of the adjusting key 92 is set for adjusting the position of the lever 95, when 45 screw 100 is loosened, each lever 95 having an edge 102 engageable by the edge 93 of key 92, the tension of spring 49 or 83 obviously co-operating with the manipulation of key 92 in forcing the lever 95 forward or backward to increase or ease 50 said tension, whereupon the screw 100 may be tightened again.

For the purpose of vibrating the ribbon at relatively slow speed and the escapement at high speed by means of a localized universal-bar mechanism, the invention may also be practiced by means of a substantially one-piece or unitary universal bar or frame, which, to this end, may be arranged relatively to the type-bar 13, as shown in Figures 5 to 9.

The heel-portion of each type-bar 13 is accordingly made substantially the same as hereinbefore described, to include a ribbon-vibrating camming edge 62^a and an escapement-actuating shoulder 80^a.

Referring to Figure 6, the camming edge 62^a is abutted in the cumbent position of the type-bar by an edge or face 103 of a unitary universal-bar frame, generally indicated by the numeral 104. Said frame 104 also presents an edge 105 arranged relatively to the type-bar-heel edge 80^a, so as to be overtaken by the latter for actuating the escapement, as will presently become clear. The edge or face 103, associated with operation of the ribbon-vibrator, may be formed by a flange 75

106 of an arcuate bar 107. A similar bar 108 presents the edge 105 which is associated with operation of the escapement.

Said bars 107, 108 and a member 111 are fastened together by rivets 110 to form the universal-bar frame 104 which has side arms 113 connected to the rockable frame 46 to support the rear of the frame 104 for fore-and-aft movement. The forward part of said frame 104 is supported for fore-and-aft movement by means of a tongue 114, slidably fitting in segment 21. A spring 116 urges the universal-bar frame 104 forwardly, the forward movement of said frame being limited, as in Figure 6, by abutment of the face 103 thereof with the camming edge 62^a of the type-bar.

The universal-bar-frame member 111 also has an upstanding flange 117 to carry the laterally-shiftable bracket 73 of the hereinbefore-described ribbon-vibrating train.

20 In the swing of the type-bar 13 from the Figure 6 position to the Figure 9 position, and beginning with the start of said swing, the camming edge 62^a of said type-bar moves the universal-bar frame 104 rearwardly with smooth acceleration indicated by the dotted lines 118, Figure 9 representing the positions of the frame 104 at equally spaced stages in the swing of the type-bar. Hence the cam-edge 62^a here, too, co-operates to raise the ribbon without liability of overthrowing or crumpling the same. As indicated in Figure 6, an escapement-actuating rear edge 119 of the frame 104, opposite the dog-rocker 29, is normally spaced forwardly of said dog-rocker, so that the latter is not moved until the type-bar reaches the 35 Figure 9 position. The escapement-dog rocker 29 is therefore operated quickly, that is, in the relatively brief interval during which the type-bar 13 moves between the Figure 9 and the Figure 8 positions. This quick movement of the universal-bar frame 104 is effected by means of said edge 80^a during said interval. Although the ribbon still has a residue of its movement to the printing point to be completed during said interval, the liability of overthrow or crumpling of the ribbon is, nevertheless, practically eliminated, since said residue of movement is small, and hence the speed of the ribbon during said interval is very much less than where, as heretofore, the full amplitude of ribbon-vibration took place during said interval. Conversely, during the recoil stroke of the type-bar from the Figure 8 position, the universal-bar frame 104 at first moves quickly forward under the pull of spring 116 as the type-bar moves from the Figure 8 to the Figure 9 position, and, in this part 50 of the type-bar recoil stroke, the dog-rocker 29 quickly completes its reciprocatory movement. As the type-bar further returns, from the Figure 9 position to the Figure 6 position, the universal-bar frame 104, still moving forward under the pull 55 of spring 116, follows the camming edge 62^a, so that the return of the ribbon from the printing point is effected at relatively slow speed.

It will be seen that the novel universal-bar mechanism is localized so that it occupies very little more room than was heretofore occupied by the single Underwood universal bar; and it will be further seen that the connections from said mechanism to the ribbon-vibrator 36 and the escapement-dog rocker 29 may be arranged as in prior machines, and that the invention may therefore be applied at little expense.

Variations may be resorted to within the scope of the invention, and portions of the improvements may be used without others.

75 Having thus described my invention, I claim:

1. In a typewriting machine, a system of individually-operable type-actions, each including a reciprocatory type-operating member, and two universal bars mounted for individual movement, one bar operable to actuate a ribbon-vibrator, and the other bar operable to actuate an escapement, each type-operating member having a cam for actuating the ribbon-vibrator at relatively slow speed, by traversing, with the cam contour, the corresponding universal bar through a protracted period of the type-action stroke, and also having a shoulder coming into play for actuating the escapement-universal bar quickly in correlation to the instant of type-impact, said universal bars being nested, next to one another, to minimize the room occupied thereby, means being provided and extending from said nested universal bars, enabling the same to respectively actuate the ribbon-vibrator and escapement.

2. In a typewriting machine having a ribbon-vibrator and an escapement-mechanism, a system of type-carriers mounted in arcuate array to swing their types to a common printing point, each type-carrier having at its fulcrum-end a cam, and also having a shoulder in sequence to the cam-contour, and a pair of universal bars, each presenting a part curved similarly to the type-carrier array, said parts nested one within the curve of the other, the outer-part bar operable by means of said cam to work the ribbon-vibrator at relatively slow speed during a protracted period of the type-carrier stroke, and the inner-part bar operable by means of said shoulder to work the escapement quickly in correlation to the instant of type-impact. 35

3. In a front-strike typewriting machine having a row of type-key levers and a system of type-carriers connected to and mounted in arcuate array above said key-levers to swing the types to a common printing point, and a pair of fore-and-aft extending universal-bar frames mounted for individual movement above the key-levers and behind the type-carriers, each frame having at its front an arcuate universal bar, the two bars being nested, one within the curve of the other, the rearwardly-extending portions of said frames also being nested, one above the other, and reaching rearwardly to coact with the ribbon-vibrator and escapement-mechanism, each type-carrier having at its fulcrum-end a cam for actuating the ribbon at relatively slow speed by engaging the corresponding curved universal bar through a protracted period of the type-carrier stroke, each type-carrier also having a shoulder coming into play after the ribbon has been vibrated substantially to the printing point, to engage the other universal bar to work the escapement quickly in correlation to the instant of type-impact.

4. In a typewriting machine, a system of type-actions, a system of pivoted cams, one cam associated with each type-action and rotatable by operation of the latter, and means forming a ribbon-vibrating universal-bar edge and an escapement-actuating universal-bar edge, said edges extending transversely of and in operative juxtaposition to the cams, each cam formed to actuate the ribbon-vibrating universal-bar edge at relatively slow speed by working through a protracted period of the type-operation, each cam having in sequence thereto a shoulder to engage the escapement universal-bar edge to operate the escapement quickly, close to the instant of type-impact. 60

5. In a typewriting machine, the combination 75

with a system of type-actions, each having a reciprocating type-carrier operable to bring its type to and from a common printing point, a ribbon-vibrator and a letter-feed escapement, of means whereby any type-carrier by its swing to and from the printing point actuates said vibrator and escapement, so that the escapement is worked quickly during a brief period of said movement, close to the instant of type-impact, and so that the ribbon-vibrator is actuated at relatively slow speed by being worked through a substantially more protracted period of said type-carrier movement than the escapement.

6. In a typewriting machine, the combination with a system of type-carriers pivoted in arcuate array, of a universal-bar mechanism operable at sequential phases of and by the type-carrier swing and including a plurality of curved universal bars mounted for individual movement, said bars being nested, curve within curve, in operative juxtaposition to the type-carriers, each type-carrier having means enabling it in its swing to engage said bars consecutively.

7. In a front-strike typewriting machine, a system of type-carriers mounted in arcuate array to print at a common printing point, a pair of curved universal bars nested, one within the curve of the other, and arranged relatively to the type-carriers for individually timed actuation by any type-carrier, each universal bar forming part of a frame extending rearwardly, the rearwardly-extending portions also being nested, one above the other, the frames being mounted for individual movement, an escapement member operable by means of the rear portion of one frame, and a ribbon-vibrating train operable by means of the rear portion of the other frame.

8. A type-action member for use with a universal-bar device of the character described, and mountable to swing about a fulcrum, said member having, coaxial with said fulcrum, a cam to displace said universal-bar device during a protracted period of the swing of said member, and also having, spaced in sequence to the cam, a shoulder to actuate said device at the end of said period.

9. In a front-strike typewriting machine, a system of type-carriers, a segment mounting the type-carriers in arcuate array to bring their types to a common printing point, and a pair of frames, each having a curved universal bar engageable by the type-carrier, one universal bar nested within the curve of the other, the frames extending rearwardly from the universal bars to operate respectively a ribbon-vibrator frame and an escapement mechanism, each frame guided at the front by said segment for fore-and-aft movement, means being provided to guide said frames at the rear for such movement, each type-carrier having a cam to operate the ribbon-vibrator universal bar and also having a shoulder to operate the escapement universal bar.

10. In a typewriting machine, a universal bar operable by a system of type-actions and disposed at the interior of the machine, said bar having an arm extending in substantially the direction of its movement to reach a part of a universal-bar-operated mechanism, said arm being divided, one arm-portion overlapping another arm-portion lengthwise of the arm, said portions adjustably fastened together, one arm-portion having a tool-receiving fulcrum, and the other arm-portion having, contiguous to said fulcrum, an edge, said fulcrum and edge enabling the turning of a tool applied thereto from a side of the

machine to effect lengthwise movement of one arm-portion relatively to the other arm-portion, for fine adjustment of the universal-bar structure relatively to said type-actions and said operated mechanism.

11. A universal bar constructed according to claim 10, one arm-portion having a tool-receiving hole, and the other arm-portion having edges on opposite sides of said hole, said hole and edges enabling the turning of a tool applied thereto to effect shortening or lengthening of said arm for the aforesaid adjustment.

12. In a typewriting machine having a universal bar; a spring for urging said bar in one direction, a spring-support, and a mounting to which said spring-support is clamped in variable position, said mounting and support being at the interior of the machine and having a fulcrum on the one and a contiguous edge on the other, said fulcrum and edge enabling the turning of a tool applied thereto from the outside of the machine to shift said spring-support for tensing or easing the spring.

13. In a typewriting machine, the combination with a system of key-operated reciprocating type-carriers mounted in arcuate array and operable to bring their types to and from a common printing-point, a ribbon-vibrator and a letter-feed escapement, of individual universal bars for the ribbon-vibrator and escapement, said type-carriers having means to operate the universal bars separately, so that the ribbon-vibrator is operated during a protracted period of the type-bar stroke and the escapement is operated only during a brief period of said stroke near the instant of type-impact.

14. In a typewriting machine having a ribbon-vibrator and an escapement, a system of type-carriers mounted to swing individually to bring their types to a common printing point, and a universal-bar mechanism connected to actuate the ribbon-vibrator and escapement, each type-carrier having at its fulcrum-end a cam to engage a portion of said universal-bar mechanism through a protracted period of the type-carrier stroke, and thereby operate the ribbon-vibrator at a relatively slow speed, each type-carrier also having near its fulcrum-end a shoulder coming into engagement with another portion of said universal-bar mechanism for a brief portion of the type-carrier stroke to thereby work the escapement quickly near the instant of type-impact, said portions of the universal-bar mechanism being localized in contiguity to one another and in operative contiguity to said cams and shoulders.

15. In a typewriting machine having a ribbon-vibrator and a letter-feed escapement, a system of type-actions with which is associated a system of reciprocating shouldered cams, one cam for each type-action and rotatable by the latter, during the printing and return strokes, and a universal-bar mechanism connected to actuate the ribbon-vibrator and escapement, each cam formed to engage and actuate a portion of said universal-bar mechanism through a protracted period of the type-action stroke for actuating the ribbon-vibrator at relatively slow speed, each cam having a sequence to its ribbon-vibrating contour a shoulder to engage another portion of the universal-bar mechanism to operate the escapement quickly close to the instant of type-impact.

16. In a typewriting machine, a system of individually-operable type-actions, a co-operating

- letter-feeding escapement, each type-action including a key-member operable in printing and return strokes, each type-action also including a type-operating member driven by said key-member through a movement-multiplying connection so as to have greater amplitude of stroke than said key-member during the printing and return strokes of the type-action, a ribbon-vibrator, and two universal bars mounted for individual movement, one universal bar connected to actuate the ribbon-vibrator, and the other universal bar connected to actuate the escapement, each of said type-operating members having means for actuating the ribbon-vibrator at relatively slow speed by working the corresponding universal bar through a protracted period of type-operating member stroke, and each of said type-operating members also having initially idle means, effective only during a brief part and near the completion of its relatively great printing stroke, for completely operating the escapement-universal bar quickly near the instant of type-impact, said universal bars being nested, one within the other, to minimize the room occupied thereby.
17. In a typewriting machine, a system of individually-operable type-actions, each including a type-operating member driven by a key-member and having a substantially greater amplitude of movement than said key-member during the printing and return strokes, a letter-feed escapement, a ribbon-vibrator, and a universal-bar-mechanism connected to actuate the escapement and ribbon-vibrator, each of said type-operating members including a cam for actuating the ribbon-vibrator at relatively slow speed by engaging and traversing a portion of said universal-bar mechanism through a protracted period of the type-action stroke, each of said type-operating members also having a shoulder, initially idle, and only coming into play to engage another portion of said universal-bar mechanism for a brief period near the completion of the relatively great printing stroke of said type-operating member, to thereby completely operate the escapement quickly close to the instant of type-impact, said portions of the universal-bar mechanism comprising two faces, one face for engagement by said cam, and the other face for engagement by said shoulder, said faces being juxtaposed next to one another to localize the same, and thereby compact said universal-bar mechanism.
18. In a typewriting machine, a system of type-operating members movable in opposite directions for bringing types to and from the printing-point, each member including a cam and a shoulder in sequence to said cam, a universal-bar mechanism partly operable by any cam and partly by any shoulder, and a ribbon-vibrator and letter-feed escapement operable by the universal-bar mechanism, the period of ribbon-vibration being protracted through a substantial portion of the movement of said type operating member by means of said cam, said cam being formed to

cause the universal-bar mechanism to work with accelerated and decelerated movement as compared with substantially even movement of said type-operating member, whereby liability of crumpling or overthrowing the ribbon is minimized, said shoulder of the type-operating member only coming into play near the end of the printing stroke to coact with said universal-bar mechanism and effect quick and complete operation of the escapement near the instant of type- impact. 5

19. In a typewriting machine, a system of individually-operable type-actions printing at a common printing-point, each type-action including a key-member operable in printing and return strokes, and also including a type-operating member driven by, and having a movement-multiplying connection to, said key-member so as to have a stroke of substantially greater amplitude than said key-member, and two universal bars respectively connected to actuate a ribbon-vibrator and a letter-feed escapement, each type-operating member having a cam for actuating the ribbon-vibrator at relatively low speed by working the corresponding universal bar through 25 a protracted period of the printing-stroke of the type-operating member, each type-operating member also having a shoulder, initially idle, coming into play only near the completion of its printing-stroke, to impart a staccato stroke to the 30 escapement-universal bar, and thereby complete the operation of the escapement close to the instant of type-impact.

20. In a typewriting machine, a system of type-action members movable in opposite strokes for 35 bringing types to and from the printing-point, a ribbon-vibrator, a letter-feed escapement, and a universal-bar mechanism operable to actuate the ribbon-vibrator and escapement consecutively, each of said type-action members having a cam 40 whereby the universal-bar mechanism is worked, for ribbon-vibration, through a protracted period of the stroke of said member, said cam being formed to effect acceleration and deceleration of the ribbon-vibrator movement, whereby liability 45 of ribbon crumpling or overthrow is minimized, said type-action member also having a shoulder coming into play near the end of its printing-stroke, to give a rapid impulse to the universal-bar mechanism to actuate the escapement quickly, near the instant of type-impact, in contradistinction to the decelerated movement of the ribbon-vibrator.

21. In a typewriting machine, the combination with a system of type-carriers pivoted to swing 55 from an arcuate array, a ribbon-vibrator, and a letter-feed mechanism, of a universal-bar mechanism arranged for actuating the ribbon-vibrator and letter-feed mechanism consecutively, each type-carrier having a cam and a shoulder for engaging the universal-bar mechanism at consecutive phases of the type-carrier swing. 60
